W. H. SINCLAIR.
RIBBON ATTACHMENT ESPECIALLY ADAPTED FOR TYPEWRITERS.
APPLICATION FILED OCT. 26, 1921.
1,420,874. Patented June 27, 1922.

UNITED STATES PATENT OFFICE.

WILLIAM H. SINCLAIR, OF BERKELEY, CALIFORNIA, ASSIGNOR TO MANIFOLD IMPRESSIONS CORPORATION, OF CARSON CITY, NEVADA, A CORPORATION OF NEVADA.

RIBBON ATTACHMENT ESPECIALLY ADAPTED FOR TYPEWRITERS.

1,420,874.

Specification of Letters Patent. Patented June 27, 1922.

Application filed October 26, 1921. Serial No. 510,411.

To all whom it may concern:

Be it known that I, WILLIAM H. SINCLAIR, a citizen of the United States, residing at Berkeley, in the county of Alameda and State of California, have invented 5 certain new and useful Improvements in Ribbon Attachments Especially Adapted for Typewriters, of which the following is a specification.

10 My invention relates in general to the art of manifolding for the production of what are known as carbon-copies of original impressions made by typewriters and similar machines; and it especially relates to mani- 15 folding devices associated with the platen-carriage of such machines, and comprising one or more suitable impression ribbons and means for moving them into and out of functional position between the sheets of 20 paper in the line of type-impact.

In devices of this nature, it is proposed to employ a single length of impression ribbon, provided with a clip at each end, adapting the ribbon to be readily connected with 25 and detached from a pair of spaced arms, between which it is stretched and carried under proper tension parallel with and approxi- 30 mately the length of the machine platen. Such a ribbon, necessarily has a relatively short life, and it is, therefore, of importance that it be capable of being attached and detached with ease, and should also be cheap to manufacture, consistent 35 with the necessary strength to resist and sustain the tension of its mounting. One of the factors in the problem is the clips or end attachments by which the ribbon is connected with the carrying arms; and it is particularly to this factor that my present 40 invention is directed, the object of said invention being to provide an impression ribbon for this purpose which is economical to manufacture, can be readily attached and detached, and has the required strength in 45 its attachment to resist the tension strain under which it is carried.

To this end my invention consists in the novel ribbon attachment for the described purpose, which I shall now fully describe, 50 by reference to the accompanying drawings, in which—

Fig. 1 is an end view of the platen carriage of a typewriter, showing one form

of a manifolding device to which my ribbon attachment is applicable.

55

Fig. 2 is perspective view showing the ribbon attached to the carrying arms of the manifolding device.

Fig. 3 is a perspective view, enlarged, of one end of the ribbon, showing the application thereto of the clip member in its blank or initial form.

60

Fig. 4 is a perspective view of the same, showing the first fold of the clip attachment.

65

Fig. 5 is a perspective view of the same showing the final or completed fold of the clip attachment.

65

Fig. 6 is a sectional view of Fig. 5, showing in addition the application of the completed clip to the notch of the carrying arm.

70

Fig. 7 is an elevation of a modification of the shape of my clip attachment, showing it in its blank or initial form.

Fig. 8 is an elevation of the same completed and applied to an inclined end of the carrying arm.

75

1 is the impression ribbon. This may be of suitable material, say, for example, a textile fabric.

80

To each end of the ribbon is applied a clip member 2, as shown in Fig. 2. This clip member is made of some relatively cheap material, in practice, of paper. The paper blank, as shown in Fig. 3, comprises 85 a body portion *a* and two wing portions *b*.

The body portion is placed upon and secured, as by adhesion, to the end of the ribbon, and both are preferably, though not necessarily, indented, as shown at 3 on each 90 side, to better define the line of fold and to form a bight more easily adapted for the entrance of the carrying arm as will presently appear.

After the clip blank 2 has been initially 95 applied, as in Fig. 3, the end of the ribbon and the body of the clip are folded inwardly as shown in Fig. 4, the adjacent surfaces of the ribbon being caused to adhere, except at the bight, which is left free and open as 100 in Fig. 5, which result may be had by making the fold over a rod, for example. Then, as shown in Fig. 5, the side wings *b* are folded over on the body *a* of the clip and are caused to adhere thereto. The clip attachment is thus completed, and may be 105

fitted upon the notch 4' in the ends of the arms 4 of the mounting, as shown in Figs. 2 and 6.

It will now be seen that although the clip 5 is made of relatively frail and cheap material, it will stand any required tension strain placed upon it, when the ribbon is stretched between the arms 4, because the strain is borne by the relatively stronger ribbon itself, which is folded in the securing bight and forms part of the clip attachment. In Fig. 2, the numeral 5 is a rod forming the axis of movement of the ribbon to and from its functional position, as shown in Fig. 1, 10 in which 6 is the platen-carriage of a typewriter, 7 is the platen, 8 is one of the brackets which carry the rod 5, and 9 is the paper-guide apron. This assemblage represents one form of manifolding devices for typewriters, with which my ribbon attachments 20 may be used, though it is to be understood that any device employing movable carrying arms between which the ribbon is stretched under tension may be adapted for the novel 25 clip attachment of my ribbon.

In Figs. 7 and 8, I show my clip attachment in slightly modified contour adapting it for an angular securing bight to provide for a certain adjustment or restoration of 30 tension, if the ribbon should become slack. In this shape, the end of the ribbon and the end of the body portion *a* of the paper clip 2 are cut on an angle as shown in Fig. 7 and the side wings *b* of said clip are out of 35 line with each other. A diagonal line of holes 10 perpendicular to the angled edge is made through both ribbon and clip body, and the bight fold is made along said line of holes, after which the opposite wing is 40 folded down as shown in Fig. 8. The end of the carrying arm 4 is inclined as shown at 11 and is provided with tongues 12 which engage the holes 10 in the bight of the clip. The object of this angular connection is, 45 by setting the clip to different positions along the inclined end of the arm 4, to restore the tension of the ribbon, if it should become slack. This angular connection, however, is not per se my invention, the object in showing it herein being merely to 50 illustrate a modified shape of my clip in so far as the essential combination of ribbon and paper and their folding are concerned.

It may be further noted that my ribbon

attachment as herein described provides a 55 convenient and cleanly means for the operator to take hold of the ribbon, in the act of placing it in the manifolding device or removing it therefrom, since the grip of the hands will be on the clip member 2, and the 60 ribbon itself need not be touched.

It will also be seen that the side wings *b* of the clip member are so shaped and related to the body portion *a* that when folded down to final place they will leave the bight 65 of the attachment open at each end as shown in Figs. 5 and 8, to enable it to be passed upon and fitted to the carrying arms.

I claim:—

1. A typewriter ribbon attachment comprising an end portion of the ribbon, and a clip composed of a body portion secured upon the ribbon end portion, and wing portions projecting laterally from said end portion, said ribbon end portion and said body 70 portion of the clip being folded to form a terminal bight for connection with a carrying arm, and said wing portions being folded upon and secured to the folded exterior of the body portion. 80

2. A typewriter ribbon attachment comprising an end portion of the ribbon, and a clip composed of a body portion secured upon the outer surface of the ribbon end portion, and wing portions projecting laterally from said end portion, said ribbon end portion and said body portion of the clip being folded inwardly to form a terminal bight for connection with a carrying arm, and said wing portions being folded upon 85 and secured to the folded exterior of the body portion. 90

3. A typewriter ribbon attachment comprising an end portion of the ribbon, and a clip composed of a body portion secured 95 upon the ribbon end portion, and wing portions projecting laterally from said end portion, said ribbon end portion and said body portion of the clip being folded to form a terminal bight for connection with a carrying arm, and said wing portions being folded 100 upon and secured to the folded exterior of the body portion in position to leave the ends of the terminal bight open.

In testimony whereof I have signed my 105 name to this specification.

WILLIAM H. SINCLAIR.
